CAR UNDERFRAMING.

APPLICATION FILED DEC. 29, 1919.

Patented June 29, 1920.

2 SHEETS—SHEET 2.

UNITED STATES PATENT OFFICE.

WILLIAM M. RYAN, OF CHICAGO, ILLINOIS, ASSIGNOR TO THE RYAN CAR COMPANY,
A CORPORATION OF MAINE.

CAR-UNDERFRAMING.

1,345,258.

Specification of Letters Patent. Patented June 29, 1920.

Application filed December 29, 1919. Serial No. 347,984.

To all whom it may concern:

Be it known that I, WILLIAM M. RYAN, a citizen of the United States of America, and resident of Chicago, county of Cook, and 5 State of Illinois, have invented certain new and useful Improvements in Car-Underframing, of which the following is a specification, and which are illustrated in the accompanying drawings, forming a part 10 thereof.

The invention relates to underframing for railway cars and has as an object the provision of a structure that may be placed under existing cars which need reinforcing 15 and which will reliably withstand the stresses arising from draft and buff, as well as stiffen the frame of the car.

An illustrative embodiment of the invention is shown in the accompanying drawings in which—

Figure 1 is a plan view partly broken away;

Figs. 2 and 3 are detail vertical transverse sections on lines 2—2 and 3—3 respectively 25 of Fig. 4, but drawn to a larger scale and showing more of the bolster than does Fig. 4;

Fig. 4 is a detail plan view of one end of the structure of Fig. 1, drawn to an enlarged scale;

Fig. 5 is a detail vertical section on line 5—5 of Fig. 4, and

Fig. 6 is a detail side view of the end of a channel iron showing a step in manufacture.

The invention disclosed in this application is an improvement on that disclosed in an application for patent filed by myself September 16, 1919, Serial No. 324,197, for 40 sub sills and draft arms.

The usual bolsters of an existing car are indicated at 10 and the sills of such a car at 11. The sills 11 may be, and in cars which need reinforcing usually are, of wood. 45 Draft arms provided by the invention are indicated at 12, 13, and 14, 15, sub sills at 16, 17. The draft arms are provided with draft lugs 18 and buffing lugs 19, with holes, as 20, to receive bolts, not shown, for attachment to the wooden sills 11.

The draft arms are shown as extended through opening in the bolster and as provided with a shoulder, as 21, adapted to abut against the bolster to transfer buffing 55 stresses to the bolster. The draft arms are

channel-shaped in cross section and are preferably nested with the end of the sub sills 16, 17, and riveted thereto, as at 22. A second offset, as 23, is shown in the upper flange 24 of the draft arm in Fig. 5 by means 60 of which the upper surface of the flange 24 and of the upper flange 25 of the sub sill 16 may be brought into a common plane for reception of gusset plate 26 which is shown as riveted to the two flanges 24 and 25 at 65 27 and to the upper flange of the bolster at 28, 29.

The ends of the sub sills 16, 17, are shown as reduced in width from a point 30, Fig. 5. This reduction in width may be readily 70 produced by removal of a V-shaped piece, as shown in Fig. 6, and the closure of the gap by bending the lower side upwardly, as indicated by the dotted lines in said figure. Preferably, a row of rivet holes, as 31, 75 32, is provided on each side of the gap which rows of holes will be parallel when the reduction of width is completed and through which holes the rivets 22 may be passed.

With the ends of sills 16 and 17 reduced 80 as described and the parts assembled as shown, a gusset plate 33 may be secured to the inclined portions of both sill flanges and to the lower flange of the bolster. A bottom cover plate, as 34, connecting the lower 85 flanges of sills 16 and 17 may abut the gusset plate 33 at the point 30. A gusset plate 35 is shown connecting the bottom flanges of the draft arms and as connected to the upper surface of the bottom flange of the bolster 90 as at 36.

It is necessary to cut the gusset plates out at their central portions to permit their ends to extend forwardly for attachment to the bolster. To prevent danger of tearing which 95 would be caused by an angle, the cut out portions are formed on curves, as shown at 37, 38, 39.

I claim as my invention:

1. In an underframe for railway cars, in 100 combination, a pair of body bolsters, channel shaped sub sills extending between the bolsters, channel shaped draft arms of less width than said sills extending through the bolsters and nesting with and connected to 105 the sills, portions of the lower flanges of the sills being upwardly inclined whereby the width of the sills at the ends is reduced, and a gusset plate secured to said inclined portions of the sills and to the bolster. 110

2. In an underframe for railway cars, in combination, a body bolster, sub sills, draft arms, gusset plates connecting the sills together and the draft arms together and each 5 to the bolsters, said gusset plates being cut away at their center portions to provide forwardly extending arms, the angles between said arms and said central portion being rounded to prevent tearing.
- 10 3. In an underframe for cars, in combination, a bolster, a draft arm extending through the bolster, a sub sill of greater vertical dimension than the arm secured to the latter, the lower margin of the sill adjacent 15 to the bolster being upwardly inclined, and a gusset plate attached to the inclined portion and to the bolster.
- 20 4. In an underframe for cars, in combination, a bolster having flanges upon its lower margin, a pair of sub sills back of the bolster, the body portion of the sills extending below the lower margin of the bolster, the lower margins of the end portions of the 25 sills being upwardly inclined and a gusset plate secured to the inclined portions of the sills and to the upper faces of the bolster flanges.
5. In an underframe for cars, in combination, a bolster, a sub-sill extending to the
- bolster, a draft arm having a portion of less 30 width than the sub-sill extending through the bolster, the end of the sub-sill being reduced in width by removal of a V-shaped piece and closure of the gap in such a manner that the resulting joint is parallel with 35 the sub-sill, and a row of rivets on each side of the joint passing through the sub-sill and through the projection of the draft arm.
6. In an underframe for cars, in combination, a bolster, a draft arm extending 40 through the bolster, a sub sill of greater vertical dimension than the arm secured to the latter, the lower margin of the sill adjacent the bolster being upwardly inclined, a gusset plate attached to the inclined portion and 45 to the bolster, and a gusset plate attached to the draft arm and to the bolster.
7. In an underframe for cars, in combination, a bolster having an I section, sub sills and draft arms extending in opposite directions from the bolster gusset plates secured to the upper and lower margins respectively of the sub sills and to the lower margin of the draft arms, said gusset plates being each 50 secured to inwardly facing surfaces of the 55 flanges of the bolster.

WILLIAM M. RYAN.
